UNITED STATES PATENT OFFICE.

JOHN BURCHAM, OF ALBUQUERQUE, NEW MEXICO.

AUTOMATIC FLUSH TANK AND DEODORIZER.

Application filed June 19, 1926. Serial No. 117,106.

This invention relates to flush tanks such as are used on toilet bowls and closets and the general object of the invention is to provide in combination with the flush tank, 5 a tank for a liquid deodorizer and provide means whereby when the outlet valve of the flush tank is opened, the outlet valve of the deodorizer tank will also be opened so as to discharge a certain amount of deodorant 10 into the water passing from the flush tank.

My invention is illustrated in the accompanying drawings wherein:—

Figure 1 is a vertical sectional view through a flush tank constructed in accordance with my invention;

Fig. 2 is a front elevation of the controlling valve, showing the means whereby the controlling valve may be adjusted;

Fig. 3 is a sectional view through the support for the handle 32;

Fig. 4 is a sectional view of the bracket which supports the lever;

Fig. 5 is a sectional view through the outer shell of this bracket.

Fig. 6 is a perspective view of the stop 43.

Referring to these drawings 10 designates a flush tank having a water inlet pipe 11 controlled by a valve 12, in turn controlled by a lever 13 mounted upon the lever 14. A 30 float 15, is mounted upon the rod 16 which extends up through the lever 13 and is held in adjusted position by means of the two nuts 17.

The flush tank is provided with the outlet 35 pipe 18 which is connected by a pipe section 19 with a pipe 20 leading from a deodorant containing tank 21. In the length of this pipe 20 is provided a valve casing 22 having a valve therein controlled by an arm 40 23, this arm being held in clamped engagement with the valve by means of the screw 24.

A flush valve 25 may be used to control the flow of water through pipe 18, this 45 valve being mounted upon an overflow pipe 26 which is connected by a bail 26^a to the lever 27 mounted upon a supporting bracket 28 and the other end of the lever from the rod 26 is connected by a rod 29 to a slightly 50 angular lever 30 mounted upon a supporting bracket 31. Preferably the overflow pipe 26 extends through the valve plug 25.

Mounted upon the outer face of the tank 55 is a handle 32. The oscillatable stem 33 to which this handle is connected has an arm

34 which in turn is connected by a link 35 to the arm 23 and the lever 30 is connected at its end remote from the rod 29 to the link 35. Thus, it will be obvious that as the handle 32 is lifted, the outer arm of the 60 lever 30 will be raised thus pulling downward on the rod 29, thus lifting the flush valve 25 from its seat, permitting the discharge of water from the tank. The coincident opening of the valve in casing 22 65 permits a certain amount of deodorant to pass downward through the pipe 20 and mix with the flushing water.

The lever 27 and the levers 30 and 34 are mounted upon brackets, one of which is 70 illustrated in Figure 4. All of these brackets are alike and, therefore, I will describe the one used in connection with the lever 27. The stem or fulcrum of this lever is constituted by a bolt 36 which passes through a 75 sleeve 37. This sleeve is formed as part of a conical bracket 38 having a broad flat base 39 which abuts against the wall of the tank. The outer end of this bracket is flanged so as to provide a firm support for the lever 27. 80

The valve seat 40 has a head 41 which rests in a recess or countersink in the bottom of the tank. The valve seat is screw-threaded for engagement by a nut 42 which draws head 41 in water tight engagement with the seat. The float arm 13 is limited in its 85 upward movement by a stop 43 which is slotted so that it may be adjusted, and the lower end of this stop is forked and extends down on each side of arm 13.

The operation of this mechanism will be obvious from what has gone before. When it is desired to flush the bowl the handle 32 is shifted which lifts up on the link 35, opening the deodorizer valve in the casing 22 and at the same time opening the flush valve 25. The water passes out into the bowl along with a certain amount of deodorizer. This deodorizer valve can be adjusted to let any desired quantity of the deodorizing fluid pass out into the discharge pipe 18. When the water has descended in the tank to a predetermined height, the flush valve will close and the float 15 having lowered, the valve 12 will be raised from its seat, permitting the inlet of water until the float valve 12 has raised to its normal position when the valve 12 will close.

As a means for adjusting the valve within 100 casing 22 so as to control the amount of de-

odorant which will pass into the pipe 18, I form the arm 33 so that it may be adjusted upon the valve spindle or, in other words, so that the valve spindle may be adjusted with reference to this handle to cause a greater or less opening of the valve upon a full elevation of the arm 23 as the handle 32 is actuated.

I claim:—

10. In combination with a flush tank provided at its bottom with a valve controlled outlet, a deodorizer tank mounted thereon and having a valve controlled pipe connected with the outlet of the flush tank, a lever fulcrumed in the flush tank and having one end operatively connected with the outlet valve, a rocker lever fulcrumed in the flush tank below the deodorizer tank, means operatively connecting said levers together, a handle

20. shaft journaled in the flush tank below the deodorizer tank and having its axis disposed parallel with the axis of pivotal movement of the rocker lever, said handle shaft being provided with an angularly disposed arm, an arm carried by the valve in the pipe which connects the deodorizer tank with the flush tank outlet, and a toggle link having angularly disposed end portions, one 25. end portion being pivotally connected with the arm upon the handle shaft and the other end pivotally connected with the arm upon said valve stem, and one end of the rocker lever being pivotally connected with the toggle link substantially at the apex of the angle between the end portions thereof.

30. 35. In testimony whereof I hereunto affix my signature.

JOHN BURCHAM.
